US00D998153S

(12) **United States Design Patent** (10) **Patent No.:** **US D998,153 S**
(45) **Date of Patent:** **** Sep. 5, 2023**

(54) **SPHYGMOMANOMETER**

(71) Applicant: **Shenzhen YuanRui Information Technology Co., Ltd**, Shenzhen (CN)

(72) Inventor: **Jin-Long Lin**, Brea, CA (US)

(73) Assignee: **Shenzhen YuanRui Information Technology Co., Ltd**, Shenzhen (CN)

(**) Term: **15 Years**

(21) Appl. No.: **29/828,419**

(22) Filed: **Feb. 25, 2022**

(51) LOC (14) Cl. **24-01**

(52) U.S. Cl.

USPC **D24/165**

(58) **Field of Classification Search**

USPC D24/107, 164-168, 186; D10/70, 75, 78;

D14/344

CPC A61B 5/0402; A61B 5/0404; A61B 5/021;

(57) **CLAIM**

The ornamental design for a sphygmomanometer, as shown and described.

DESCRIPTION

FIG. 1 is a front, right, and top perspective view of a sphygmomanometer, showing my design.

FIG. 2 is a rear, left, and bottom perspective view of the sphygmomanometer in FIG. 1.

FIG. 3 is a front view of the sphygmomanometer in FIG. 1.

FIG. 4 is a rear view of the sphygmomanometer in FIG. 1.

FIG. 5 is a left side view of the sphygmomanometer in FIG. 1.

FIG. 6 is a right side view of the sphygmomanometer in FIG. 1.

FIG. 7 is a top view of the sphygmomanometer in FIG. 1; and,

FIG. 8 is a bottom view of the sphygmomanometer in FIG. 1.

1 Claim, 8 Drawing Sheets
